UNITED STATES PATENT OFFICE.

WILLIAM S. PATES, OF ALTON, ILLINOIS.

SULKY-PLOW.

SPECIFICATION forming part of Letters Patent No. 352,999, dated November 23, 1886.

Application filed July 19, 1886. Serial No. 208,472. (No model.)

To all whom it may concern:

Be it known that I, WILLIAM S. PATES, of Alton, in the county of Madison and State of Illinois, formerly of Jonesburg, in the county 5 of Montgomery and State of Missouri, a citizen of the United States, have invented a certain new and useful Improvement in Sulky-Plows, of which the following is a full, clear, and exact description, reference being had to 10 the accompanying drawings, forming part of this specification, and in which—

Figure 1 is a longitudinal vertical section showing the plow proper in a depressed position. The elevated position of the plow is indicated by broken lines, the changed position 15 of the hand-lever and connections being indicated in the same manner. Fig. 2 is an enlarged perspective detail view. Fig. 3 is a perspective view of the bracket by which the 20 axle and tongue are secured together, and to which the rock-bar and one arm of the lifting-bail are fulcrumed; and Fig. 4 is a perspective view of the fulcrum-bracket to which the other arm of the lifting-bail is fulcrumed. 25 Fig. 5 is a detail horizontal section through one of the fulcrum-joints of the lifting-bail, showing the double function of the tubular studs on the brackets as sleeves to the pivot-bolts that secure the bail and forming the 30 bearing on which the bail works and is fulcrumed while lifting the beam. Fig. 6 is a perspective view of the saddle-bracket, showing its elongated slot and corrugated friction-surface for the adjustment and leveling of the 35 plow. Fig. 7 is a perspective view of one of the corrugated washers that engages on the friction-surface of the saddle-bracket and seats the set-screw Z, and Fig. 8 is a section showing the means of attachment of the saddle-bracket to the bail.

My invention relates to improvements in sulky-plows, and especially to elevating, leveling, and adjusting devices in connection therewith; and my invention consists in features of novelty hereinafter fully described, 45 and pointed out in the claims.

Referring to the drawings, in which similar letters of reference indicate like parts, A represents the furrow-wheel; B, the axle, which is 50 straight instead of the usual arched axle; and B' the crank-axle, which carries the land-wheel. (Not shown.)

C is the lever for operating the crank-axle for leveling the plow, and D is the segmental rack for holding the lever C.

55

E is the spring-latch that works in the box E' and engages the teeth D' of the rack D. E' is the rod that connects the latch with the pivoted trigger E'', adjacent to the handle of the lever. The latch is projected into the 60 notches D'' of the rack by a spring, E'', behind the trigger, and holds the crank-axle in the position that the lever C has placed it, thus enabling the operator to level the plow and lock its adjustment.

65

F represents the tongue, and F' a curvilinear bar that braces the tongue to the axle, being secured to the tongue by a bolt, f, and to the axle by a bolt, p.

G is a segmental rack secured to the tongue 70 by the bolt f and also by a bolt, f'', for holding the adjustment of the bell-crank lever H, that is secured to the tongue by a pivot-bolt, H'', passing the segmental plate. This lever elevates, depresses, and adjusts the vertical 75 position of the plow.

G' are the teeth on said rack which have intervening notches, G'', between them, into which notches the spring pawl or latch I, that works 80 in the box I', is projected by the trigger-spring I'', that throws out the pivoted trigger I' from the handle of the lever, and through its connecting-rod I' springs the latch into its seat between the teeth of the rack and locks the 85 vertical adjustment of the plow either in or completely lifted from the ground.

The lever H has a bell-crank arm, H'. A link, J, is pivoted by a pin, j, at the lifting extremity of the short arm H' of the bell-crank lever, and is also pivoted by a pin, j', within 90 the bifurcated end K' of the rock bar or lever K, which is pivoted on a sleeve, K'', to the bracket N, secured by a horizontal bolt, k, passing through the sleeve K'' and through the tongue, vertical bolts n n passing through the tongue and horizontal bolt n'' passing through the axle. The bracket N thus secures the axle and tongue together, having angle-flanges at N' and N'' that relatively embrace the axle and the tongue, to which they are bolted. Within 95 the fork K'' of the rear extremity of the lever K is pivoted by a pin, k'', a pendent bifurcated bar, L, in the fork L' of which is pivoted by a pin, l, the inner arm, M', of the L-shaped

elevating-bail M, that lifts the plow-beam, and whose functions will be fully described hereinafter.

The axle end of the arm M' of the lifting-bail 5 has bearings around a tubular stud, O, that projects from the bracket N. The stud embraces the double function of a sleeve to the bolt O', that secures the bail to the said bracket, and that of a fulcrum-bearing for one arm of 10 the bail, the other arm, M'', being alike fulcrumed at its axle end on a similar tubular stud, O'', on the other fulcrum-bracket, P, through which stud a bolt, O', passes and secures the attachment of that arm of the bail. The fulcrum-bracket P has angle-flanges P', that embrace the axle to which they are bolted by the brace-bolt p.

A pendent rod, Q, is pivoted by a bolt, Q', to the rock bar or lever K back of its pivoted 20 connection with the bracket N, and its lower extremity passes through and works in a perforation, R', in the arm R, that projects from the bottom of said bracket. A spiral push-spring, S, is secured around the pendent rod 25 Q and projects against the bracket-arm R at one extremity and the shoulder Q'' below the head of the pendent rod that carries it at the other extremity. This spring pushes against the elevating end of the rock-lever sufficiently 30 in the rear of its pivoted attachment to the bracket to materially aid the operator in elevating the plow in and out of the ground, relieving the drag on the furrow-tread, and giving also a lively reactionary movement to the 35 plow, more fully pointed out hereinafter in the description of its operation.

The plow may be the ordinary plow, T, provided with the beam U.

A clip, V, formed with trunnion-pivots W, 10 is screw-clamped on the arch of the plow-beam, and can be adjusted by the operator to balance the suspension of the plow. The clip is provided with trunnions W, that work within the tubular lugs X X, which project from adjustable saddle-brackets Y Y, that straddle the rear bar of the lifting-bail, to which they are secured by screw-bolts Z Z. These saddle-brackets are provided with elongated slots Y', through which the bolts Z pass that clamp 15 them to the bail. A corrugated friction-surface, Y'', is formed on the rear surface of the saddle-bracket, and a corresponding corrugated washer, Y'', engages in the corrugations of the bracket, and on its smooth side forms 20 the seat for the set-screw Z. It will be understood that the rear bar of the bail and the washers are perforated with round holes, but the saddle-bracket has an elongated slot, Y', through which the bolt Z passes, which allows 25 of vertical adjustment to level the plow or nicely adjust the angle at which it throws its furrow. When the screw-bolt or set-screw Z is secured, the corrugations in the washer lock the adjustment in the position the operator 30 has placed it.

The operation of my sulky-plow is as follows: The clip having been adjusted on the

beam to balance the plow and regulate its draft is securely bolted thereto. Its trunnions have a free pivotal movement in the lugs X of 70 the saddle-bracket that straddles the lifting-bail, so that as the operator elevates or lowers the plow the presentation of the beam will readily conform itself to the changed line of draft. The lever H is then adjusted to lower 75 the plow to the level of its furrow-tread, and the spring-latch engaging in the rack keeps it to that adjustment until the operator changes the position of the lever.

If it is desired to elevate the plow in or out 80 of the ground, it will be seen that as the operator pulls the lever H toward him the pendent link pivoted to the bell-crank of the lever depresses the front end of the rock-lever K, the spring at the same time pushes up on the 85 rear end of the lever, thereby assisting the operator to raise the plow. The spring also releases the heavy drag on the furrow-tread and gives a lively reactive movement to the beam, that as the plow meets obstructions that 90 it could not otherwise overcome will frequently enable it with a counter and divergent movement to pass around them.

It is evident that the plow can either be raised to turn a shallow furrow only, or raised 95 completely out of the ground for removal from field to field or traveling on the road.

By the use of a straight instead of an arched axle it is found to provide a stiffer and better ballasted frame. It also gives the opportunity of working the plow-beam above the axle and provides a firm support for the fulcrum-brackets that support the lifting-bail. A further advantage of having the axle and lifting-bail beneath the plow-beam is that there are 105 no suspension-clips (on which the strain is frequently very heavy, to break and cause expense and delay.

By the use of a straight axle instead of the usual arched axle the axle performs the function of a grass-rod in breaking down all the large weeds ahead of the plow and enables the plow to turn a smooth furrow in foul land where otherwise it would choke.

The free pivoted bearings for the plow in 115 the lugs of the saddle-brackets, that are secured to the bail, allow the beam, and consequently the plow, so much more freedom of movement that impediments in its progress are more readily surmounted or passed by its reactive divergent action, and especially in gravelly soil the freedom of movement is found to result in a lighter draft.

The crank-axle with its operative devices combine with other features in this invention 125 to provide the means for leveling and adjusting the plow not only with regard to the depth of furrow but also to the angle at which it is cut and laid.

I claim as my invention—

1. The combination, with the axle B, of the 130 brackets N and P, secured on the axle, the bail M, hinged to the brackets, a plow having its beam extending over the bail and axle and

hinged to the bail, and a lever and connections between the lever and the bail for raising and lowering the plow, substantially as described.

5 2. The bracket N, formed with angle-flanges N' and N'', tubular studs or sleeves O and K'', and the arm R, substantially as described.

3. The combination, with the axle B and the tongue F, of the bracket N, having angle-flange 10 N' on the axle and angle-flange N'' over the tongue, and the bolts n and n'', by which the bracket is secured to the tongue and to the axle, respectively, substantially as described.

4. The combination, with the axle B, brackets N and P, the bail M, and plow having its beam extending over the bail and axle, of the rock-lever K, hand-lever H, rod Q, pivoted to the rock-lever and extending through an arm 15 of the bracket N, and the spring surrounding the rod, substantially as described.

5. The combination, with the axle B, the bail M, devices for raising and lowering the

bail, and a plow having its beam extending over the bail and axle, of the clip V, secured to the beam, having trunnions W, adjustable 25 saddle-brackets Y on the rear bar of the bail, having corrugated surface Y², tubular lugs X, and elongated slots Y', washers Y³, having corrugated surfaces, and the bolts Z, substantially as described.

6. The combination, in a sulky-plow, of the plow-beam extending over the axle and hinged by saddle-brackets to a lifting-bail, the said brackets having elongated slots and a corrugated friction-surface and corrugated washers 30 with set-screws, all arranged to adjust the attachment of the gang-beam to the bail and level the plow, substantially as described, and for the purpose set forth.

WILLIAM S. PATES.
